UNITED STATES PATENT OFFICE.

ANDREW LAITSCH, OF PITTSBURGH, PENNSYLVANIA.

INGOT-MOLD.

1,229,295.

Specification of Letters Patent. Patented June 12, 1917.

Application filed November 25, 1916. Serial No. 133,283.

To all whom it may concern:

Be it known that I, ANDREW LAITSCH, a citizen of the United States, residing at Pittsburgh, in the county of Allegheny and 5 State of Pennsylvania, have invented a new and useful Improvement in Ingot-Molds, of which improvement the following is a specification.

My invention relates to improvements in 10 ingot molds.

The object of my invention is to prevent breakage in ingot molds provided with what is called a "hot head." Heretofore, so far as I am aware, molds of this type were provided with, at the upper end, a portion the diameter of which was greatly in excess of the lower portion and enabled the use of what is called a "hot head;" that is, a chamber for the reception of fuel for the purpose 20 of maintaining a high temperature at that portion of the ingot mold which is called the "sink head." The portion of the mold immediately below this extended upper portion was much thinner than the remaining 25 part of the mold and when it was necessary to discharge the ingot frequent breakage occurred at this thin portion of the mold.

As before stated, the object of this invention is to prevent this breakage. I accomplish it by means of the device hereinafter described, reference being had to the accompanying drawings, forming part hereof, in which:

Figure 1 is a vertical central section of 35 my improved mold.

Fig. 2 is a section on line 2—2 of Fig. 1.

Referring to said drawings, 1 is a mold having lugs 2 cast thereon, preferably some distance below the thinnest portion of the 40 mold. The said mold may be provided with a rib 3, extending between said lugs. The upper end of said mold is surrounded by a detachable casting 4, which constitutes the outer wall of a fuel chamber 5. The upper 45 end of said mold is provided with an extension 6, formed of refractory material, the outer wall of said extension serving as the inner wall of the chamber 5. The outer wall of the casting 4 is provided with orifices 7

for the admission of air for the purpose of 50 maintaining combustion of charcoal or other suitable fuel charged in said chamber. The lower end of the mold is closed by the bottom 8.

Combustion of the fuel contained in the 55 chamber maintains a high temperature at a point coincident with the portion called the "sink head," and prevents what is termed "piping" in the ingot formed in the mold. Frequent breakage occurs in the use of the 60 ordinary mold of this type, in releasing the ingot therefrom, and this breakage occurs at the thinnest portion of the ingot mold immediately below the enlarged top portion thereof. By making the upper end of the 65 mold detachable, I avoid the danger of breakage, and avoid also the danger of having to chisel or remove overflow metal which frequently occurs in the ordinary type of "hot head" molds. 70

Over the upper end of the mold, I preferably insert a ring 9, formed of any non-conducting material, such as magnesium or asbestos fiber.

Having described my invention, what I 75 claim and desire to secure by Letters Patent, is:

A mold tapering toward the top and thinner at the upper end than at the lower end, having lugs near the upper end, in 80 combination with an auxiliary casting, constituting a combustion chamber surrounding the upper end of said mold, in combination with an extension to said mold formed of refractory material, the said space between 85 the said extension and the walls of said auxiliary casting forming a chamber for the reception of fuel, for the purpose of maintaining a high temperature at the upper end of the mold, whereby piping is prevented. 90

In testimony whereof, I have hereunto signed my name in the presence of two subscribing witnesses.

ANDREW LAITSCH.

In the presence of—

JOHN H. RONEY,

CLARENCE A. WILLIAMS.
